HOIST ATTACHMENT FOR TRACTORS

Harry S. Myers, Van, Pa.

Application May 28, 1928, Serial No. 281,167
Renewed May 12, 1932

4 Claims. (Cl. 254—166)

This invention has relation to equipment attachments for tractors and more particularly to a hoisting attachment adapted to be mounted upon the rear of the tractor and embodies the same general principle and mode of operation as the hoist attachment as shown and described and claimed in my Patent No. 1,557,470 granted October 13, 1925, for Hoist attachment for tractors.

The object of the invention is the refinement 10 of the details of construction and of attachment with a view to permitting the use of a wider and larger spool. It will be appreciated that a given space only is available between the tractive wheels and that there is also a limit to the amount 15 of overhang which is practicable in attaching a winch to the rear of the tractor.

Other objects and advantages of the invention will hereinafter appear in the following description and the novel features thereof will be particularly pointed out in the appended claims.

Like reference numerals indicate like parts throughout the several figures of the drawings in which:

Fig. 1 is a side elevation of the rear of the tractor, having a hoist attachment mounted thereto, parts of the tractor being omitted for the purpose of showing the details of construction.

Fig. 2 is a plan of the same parts.

Fig. 3 is a rear elevation of these parts with the winch spool shown in section.

Fig. 4 is an elevation of some of the parts only.

Fig. 5 is a detail showing the shifting yoke.

Fig. 6 is a perspective of a part of the frame 35 with brake band and gear guard mounted thereon.

Fig. 7 is an elevation similar to Fig. 4 taken from the other side of the machine, and

Fig. 8 is a detail of the brake band adjustment.

For the purpose of giving a clear description, 40 the hoist or winch attachment illustrated will be deemed as made up of a number of assemblies of elements as follows:

1. The frame assembly comprising all those 45 parts having no movement, such as attaching angles, side frames, guards, etc.

2. The spool assembly comprising the parts having a rotary movement and carrying the wound line.

3. The countershaft assembly comprising the pinion shift, brake lever, and associated parts.

4. The drive assembly comprising the sprockets and chain for transmitting power from the pulley shaft to the countershaft.

5. The holding pawl assembly.

6. The extension clutch control assembly.

Each of these assemblies will be described in detail and individual functions thereof pointed out. Their joint operations will then be set forth.

The skeleton winch frame is shown in Figure 6 as comprising the cross angles 10 and 11, at the ends of which are vertical angles 12 and 13. These four parts constitute a rectangular frame base and are connected together by means of suitable bolts at their junctions. To the angles 12 and 13 are attached respectively the side frame plates 14 and 15 which have been provided with suitable bolt holes which have been indicated in Figure 6 by the numerals 16, 17, 18, 19, and 20 in plate 14, and by 16', 17', 18', and 19' in plate 15. It will be appreciated that these plates extend when attached to the vertical angles rearward of the cross angles 10 and 11.

The cross angles 10 and 11 are provided with 75 bolt holes 21, 21', 22 and 22' and to the rear of these angles are attached the attaching angles 24 and 25 by means of bolts passing through these bolt holes and corresponding bolt holes in the attaching angles. The attaching angles are the means for securing the hoist attachment to the differential housing of the tractor and for this purpose they are provided each with four holes through which cap screws may be passed into the differential housing.

These attaching angles are identical in construction and either may be used as a substitute for the other. The angles 10 and 11 are further provided with bolt holes 26, 27, 28, 29 for the attachment of loops 30 and 31, which constitute 80 the means for further securing the hoist frame to the axle housings of the tractor.

Rearward of the angles 10 and 11 the frame plates are provided with the bolt holes through which the clevis bolt 32 passes and supports the clevis 33. It will be appreciated that these are duplicated on each side of the machine and constitute a means for the attachment to the winch frame of anchoring cables.

To the side plates are attached spool bearing cases 34 and 35. These cases are formed with attaching legs 36 and 37 apertured to receive bolts which also pass through the holes 18 and 19 and 18' and 19' in plates 14 and 15. These cases contain roller bearings in which is mounted 100 the shaft of the drum.

On the upper edge of the plates 14 and 15 are likewise mounted bearing cases 38 and 39 holding roller bearings in which are mounted the drive 110 shaft. It will be appreciated that these casings

have legs 36' and 37' which are apertured and constitute the means for attaching the cases to the plates. It will also be appreciated that these bearing cases are provided with suitable lubricant devices through which grease may be supplied the bearings.

A gear guard 40 is attached to the rear of the angle No. 10 and at one end of the frame and extends upward and over the pinion on the drive shaft and around the drum gear and is attached to the lower angle 11 at 40'. The guard is held steady by the connector 41 which is riveted to the guard at 42 and at its opposite end 43 is bolted to an apertured lug 44 on the bearing case 35. The guard is further secured by providing a U bolt 45 so that it might be held to the shift rod in a manner to be hereinafter described.

A sprocket guard 46 is supported at one end by the standard 47 and at its other end is secured to an apertured lug 48 rising from the bearing case 34. On this guard is mounted a throttle supporting an eye-bolt 49 in which is movable the throttle control rod 50.

The spool comprises a shaft 51 rotatable in the bearing cases 34 and 35 and held from longitudinal displacement by the closed end of said cases. Splined to the shaft are hubs 52 and 53 having formed integral therewith flanges 54 and 55, the flange 54 being extended to provide a brake drum 56 and the flange 55 being provided with bolt holes by means of which a ring gear 57 is attached to the flange. Upon shoulders on these flanges is driven a spool shank 58 and tie rods 59 are employed to secure the parts together, holes being provided in the hubs for this purpose. Spacing washers 60 and 61 lie between the hubs and the adjacent bearing case. The usual cross-over 62 is provided for the spool. Suitable provision is made for the attachment to the spool of a cable.

In the bearing cases 38 and 39 is mounted a drive shaft 63 on which slides a pinion 64, a key 65 being provided in the shaft to permit of the sliding movement of the pinion. The shaft is extended beyond the bearing case 38 and upon this extended end is mounted a collar 66 held by a suitable set screw or other means to the shaft. A large sprocket 67 is bolted to the collar 66. A chain 68 extends over the sprocket 67 and over a small sprocket 69 on the belt pulley shaft of the throttle. The parts just described are inclosed in a guard 70.

It will be appreciated that power derived from the belt pulley shaft of the throttle is transmitted from the sprocket 69 through the chain 68 to the sprocket 67 and that there is a reduction in speed in this transmission. The rotary movement of the sprocket 67 is imparted to the shaft 63, hence to the pinion 64, and to the ring gear 57 when the pinion is in mesh therewith. As shown in Figure 2 the pinion is not so meshed.

For the purpose of shifting this pinion into and out of mesh with the ring gear there is provided a rod 71 on which is slidably mounted a coupling 72 which is actuated by the shift lever 73 which has a pivotal connection at 74 to said coupling. The end 75 of the shift lever passes into a slot formed in the horizontal leg of the cross angle 10 while the upper end of said lever is provided with a suitable handle 76. It will be appreciated that when the upper end of the shift lever is moved toward the gear end of the spool it will carry the coupling 72 and since this coupling carries at its end the yoke 77 engaging a grooved end in the pinion 64, that the pinion

itself will be moved into mesh with the ring gear. The teeth on the pinion may be tapered to facilitate this meshing.

The rod 71 is mounted in apertured lug 78 on bearing case 38 and a similar lug 79 on bearing case 39. Cotter pins may be provided at the ends of the rod beyond the lugs 78 and 79 to hold the rod in position against longitudinal movement, and a cotter pin 80 as well as a washer 81 may be provided to limit the movement of the shift lever toward the sprocket end of the winch.

The rod 71 is encircled by the U bolt 45 and the clamp element 82 is inserted between the guard 40 and the rod so that the guard may be tightly secured to the rod by the nuts 83.

On the shaft 71 there is also mounted opposite the brake drum an eccentric 84 which has an extension 85 to which is bolted the brake lever 86. It will be appreciated that the rod extends through the eccentric and its extension, and as well through one end of the brake lever, so that any movement of the brake lever will be imparted to the extension and to the eccentric. A cotter pin 87 and washer 88 are employed to hold the eccentric against movement in one direction on the rod while the lug 78 will hold these parts against movement in the opposite direction. It will be appreciated that the eccentric is free to rotate on the rod.

Looped about the eccentric is one end 89 of the brake band 90 which encircles the brake drum, is held by the U clip 91 riveted to the band, and extends to a point near the angle 10, whereby a maximum of braking surface is produced. It will be appreciated that the lining 92 is riveted to the brake band throughout its gripping radius.

Adjustment of the brake band is accomplished by a novel means. The end 93 of the brake band is longitudinally curved and is welded to a sleeve 94 of material of the same general thickness and the sleeve is mounted upon a long bolt 95 passing through both the cross angle 10 and the cross angle 11, the head of the bolt lying upon the upper surface of the angle 10. Both the bolt and the sleeve extend through the hole in angle 11 and the lock nuts 96 may be employed to raise the sleeve on the bolt to any elevation desirable for the purpose of adjusting the length of the brake band, as will be appreciated from an inspection of Figure 8.

Referring to Figures 1 and 4 the brake drum as shown is provided with lugs 97 on the inner face thereof and mounted upon the plate 14 is a holding pawl 98 which may be manually lifted, into position to cooperate with a lug 97 in holding the spool against reverse movement or which may be dropped out of such engagement to permit of such movement.

The hoisting device is provided with means whereby the tractor clutch pedal may be depressed to cut off the power being delivered to the sprocket 69 from the tractor engine. This comprises a rod 99 mounted at one end in a strap bearing 100 beyond which it is formed with a crank end 101 carrying a link 102 which is hooked at its upper end to engage over the throttle clutch pedal 103, the rod is extended backward where it is supported in a second strap bearing 104 which is hung from the plate 14; this rod is bent to form a handle 105 of any desired design which will permit of its being tilted to release the clutch.

From the detailed description of the parts as they form the different assemblies comprised in the hoist attachment the functions of the several parts as well as those of the assemblies themselves

ought to be clear. It remains, therefore, for a full description only a recital of the conjoint use of the several assemblies.

Power from the tractor imparted to the 5 sprocket 69, as heretofore explained will cause a rotation in the pinion 64 and this rotation will be transferred to the ring gear where it will cause a rotation of the spool of the winch. The pinion is shifted into and out of mesh with the gear by 10 the shift lever 73 and it will be appreciated that the construction of parts involved in the pinion shifting mechanism and in the brake band mechanism is very simple. The single rod 71 which remains stationary in the machine is sufficient to 15 act as a support for the yoke, the coupling, the shift lever, and the brake eccentric. The brake eccentric is likewise very simple in that the extension is attached readily to the handle at one point, and by reason of the fact that the rod 71 passes 20 through both the lever and the eccentric there is no need for a second point of attachment between the extension of the eccentric and the lever. The adjustment of the brake band also embodies 25 a very simple construction and permits of an adjustment by simply tightening up the nuts 96 from a point which is readily accessible. The guards are simply mounted upon the frame. The frame itself is constructed of stock material and permits the widest possible spool to be used in the 30 winch.

The frame is easily attached and strongly secured to the tractor by its attachment to the differential housing and to the axle housing as well.

Having described my invention that I claim is 35 new, what I desire to secure by Letters Patent is:

1. In a piece of tractor equipment, a frame com-

prising cross angle members, attaching angles secured to the cross angles for attachment of the frame to the tractor, vertical angles secured at the ends of the cross angles, and supporting plates attached to the vertical angles, between which the equipment elements are mounted.

80

2. The combination of claim 1, in which the supporting plates extend forward and rearward of the vertical angles, the equipment elements being supported forward above and upward of the connection of plates and angles, and anchoring elements being supported upon the rear of the plates.

85

3. In a piece of tractor equipment, comprising a frame, a winch spool and shiftable drive element therefor, the sub-combination comprising a rod extending across the space occupied by the spool, and supporting bearings for said rod extending from the frame at either side of the spool, said rod carrying between said supporting bearings shifting means for said drive element and brake applying means for said spool comprising an eccentric and a handle attached to said eccentric.

90

4. In a tractor-equipment combination, a frame supporting a spool embodying a brake drum, said frame having aligned openings, a brake band for said brake drum and means for applying braking pressure to said brake band, an adjustment means for said brake band comprising a bolt passing through said aligned openings in said frame, a sleeve upon said bolt extending through one of said aligned frame openings and to which one end of the brake band is attached, and means for adjusting said sleeve upon said bolt.
